AIRCRAFT TIRE

Charles A. Bigelow, Houston, Tex.

Substituted for abandoned application Serial No.
 134,585, November 7, 1946. This application
 March 17, 1949, Serial No. 1,433

Term of patent 14 years

(Cl. D90—20)

To all whom it may concern:

Be it known that I, Charles A. Bigelow, a citizen of the United States, residing at Houston, in the county of Harris and State of Texas, have invented a new, original, and ornamental Design for an Aircraft Tire, of which the following is a specification, reference being had to the accompanying drawing, forming part thereof.

The figure is a perspective view of an aircraft tire, showing my new design.

The dominant features of my design, reside in the portions shown in full lines.

This case is a substitute for my abandoned application Ser. No. D. 134,585, filed Nov. 7, 1946.

I claim:

The ornamental design for an aircraft tire, substantially as shown and described.

CHARLES A. BIGELOW.
